United States Patent Office

Des. 228,028
Patented July 31, 1973

228,028

PAIR OF SUNGLASSES

Conrad Leblanc, Leominster, and Vitalino Marchi, Concord, Mass., assignors to Foster Grant Co., Inc., Leominster, Mass.

Filed July 15, 1971, Ser. No. 163,142

Term of patent 14 years

Int. Cl. D16—06

U.S. Cl. D57—1 D

FIG. 1

FIG. 2

FIG. 3

FIG. 4

FIG. 5

FIG. 1 is a top perspective view of a pair of sunglasses of our new design;

FIG. 2 is a bottom perspective view thereof;

FIG. 3 is a front elevational view thereof;

FIG. 4 is a front elevational view of the sunglasses with the front lens portion pivoted to a horizontal position out of the line of sight of the user; and

FIG. 5 is a rear fragmentary view of the bridge portion of the sunglasses.

The side not shown has substantially the same appearance as the side shown.

We claim:

The ornamental design for a pair of sunglasses, substantially as shown and described.
